UNITED STATES PATENT OFFICE.

CHARLES W. MITCHELL, OF NASHVILLE, TENNESSEE.

ELECTRIC SWITCH LOCK FOR AUTOMOBILES.

Application filed December 7, 1922. Serial No. 605,452.

To all whom it may concern:

Be it known that I, CHARLES W. MITCHELL, a citizen of the United States, residing at Nashville, in the county of Davidson and 5 State of Tennessee, have invented certain new and useful Improvements in Electric Switch Locks for Automobiles; and I do hereby declare the following to be a full, clear, and exact description of the invention, 10 such as will enable others skilled in the art to which it appertains to make and use the same.

The present invention has for its object to safeguard automobiles and motor vehicles having a motive plant embodying an electric ignition system so as to prevent theft and unauthorized use of the vehicle.

In accordance with the present invention, a key operated switch is provided and interposed in the various circuits whereby in one position of the movable switch member certain controlling circuits are broken, thereby preventing the starting and the functioning of the engine, and whereby in another position 25 said circuits are closed, thereby admitting of the starting and the operation of the engine in the usual way.

Other objects and advantages will be apparent and suggest themselves as the nature 30 of the invention is understood.

While the drawings illustrate an embodiment of the invention it is to be understood that in adapting the same to meet different conditions and requirements, various 35 changes in the form, proportion and minor details of construction may be resorted to without departing from the nature of the invention.

Referring to the accompanying drawings 40 forming a part of the application,

Figure 1 is a front view of a switch lock embodying the invention,

Figure 2 is a side view with the near side 45 of the casing omitted,

Figure 3 is a horizontal section on the line 3—3 of Figure 2,

Figure 4 is a vertical transverse section on the line 4—4 of Figure 2, and

Figure 5 is a rear view.

Corresponding and like parts are referred 50 to in the following description and designated in the several views of the drawings by like reference characters.

The switch lock comprises a casing 1 55 which is preferably of metal and of

rectangular structure and having a front extension 2 designed to be let into an opening formed in the instrument board when the device is in operative position. Strips 3 of insulating material are let into opposite side walls of the casing and support guide rods 4 and switch sockets 5 to which the wires of the several circuits connect. A switch member 6 of insulating material is 60 slidably mounted upon the guide rods 4 and is provided at opposite sides with switch plugs 7 for cooperation with the several switch sockets 5. A metal pin 8 is let into the switch member 6 and cooperates with the slotted end 9 of a toothed segment 10, 65 said slotted end 9 passing through an opening formed in the member 6. The toothed segment 10 is mounted upon a shaft 11 which is supported in opposite end walls of the casing 1. A pinion 13 provided on the shaft 12 is in mesh with the toothed segment 10 and operates the latter to effect a shifting of the switch member 6, whereby to 70 break certain circuits and establish certain other circuits. A key operated spindle 14 is mounted in the front extension 2 of the casing and is coupled to the shaft 12 and when said spindle 14 is rotated in either direction, the shaft 12 is correspondingly rotated, thereby effecting a lateral movement 75 of the switch member 6 with the result herein stated. A cable 15 passes through an opening 16 in the rear wall of the casing 1 and the several strands are connected to the respective switch plugs 7. Corresponding 80 wires connect with the respective sockets 5 and as a result of this arrangement, movement of the switch member 6 in one direction closes the circuit at one side and breaks the circuit at the opposite side and upon reversing 85 the switch member 6, the circuits previously broken are closed and those previously closed are broken. Inasmuch as the switch can be operated only by a special key and since the switch is disposed in the rear 90 of the instrument board and in such position as not to be readily tampered with, it will be understood that when the switch is thrown to break the operating circuit, the vehicle cannot be started or operated, hence 95 is protected against theft and misappropriation.

A wire 18 extends to a light, not shown, suitably disposed in the car. A wire 19 extends to the horn. When the switch mem- 100
105
110

ber 6 is moved to close the circuits including the wires 18 and 19 and any one attempts to operate the car by closing the main switch, the car is flooded with light and the 5 horn is sounded thereby giving both a visual and an audible signal. The wire 20 leads to the usual headlights and the wires 21 to the timer or commutator as the case may be according to the character of the ignition system with which the car may be equipped.

What is claimed is:

1. A motor vehicle switch lock including a casing, a key-operable shaft disposed therein, a shaft substantially parallel with said shaft, a gear member on the second shaft driven from the first shaft, a contact member within the casing, means slidably mounting the contact member disposed substantially at a right angle to said shaft, contacts 15 within the casing to coact with the contact member, and a pin and slot driving connection between the gear member and said contact member.

2. A motor vehicle switch lock comprising a casing, members of insulating material at 20 opposite sides of the casing, switch elements carried by the said members, a movable switch member of insulating material mounted in the casing and provided with switch 25 elements to coact with the respective fixed switch elements, a toothed segment for effecting lateral movement of the switch member, and a key operated element in cooperative

relation with the toothed segment for actuating the same.

3. A motor vehicle switch lock comprising a casing, fixed switch elements at opposite sides of the casing and electrically insulated from one another, transverse guides, a switch member mounted upon said guides and provided at opposite sides with switch elements electrically insulated from one another and adapted to coact with the respective fixed switch elements, and a key operated mechanism for operating the movable switch member.

4. A motor vehicle switch lock comprising a casing, fixed switch elements at opposite sides of the casing and electrically insulated from one another, transverse guides, a switch member mounted upon said guides and provided at opposite sides with switch elements electrically insulated from one another and adapted to coact with the respective fixed switch elements, a toothed segment pivoted within the casing and having an extension 50 engaging the movable switch member, and a key operated shaft in engagement with the toothed segment for operating the same.

In testimony whereof I affix my signature 55 in presence of two witnesses.

CHARLES W. MITCHELL.
